ERNEST E. WANGELIN, OF BELLEVILLE, ILLINOIS, ASSIGNOR TO TWENTIETH CENTURY BRASS WORKS, OF BELLEVILLE, ILLINOIS, A CORPORATION OF ILLINOIS.

DRINKING-FAUCET.

1,278,403.

Specification of Letters Patent. Patented Sept. 10, 1918.

Application filed March 2, 1918. Serial No. 220,067.

To all whom it may concern:

Be it known that I, ERNEST E. WANGELIN, a citizen of the United States, residing at Belleville, in the county of St. Clair and 5 State of Illinois, have invented certain new and useful Improvements in Drinking-Faucets, of which the following is a full, clear, and exact description, reference being had to the accompanying drawings, forming 10 a part hereof.

The present invention is directed to improvements in drinking faucets commonly known as bubbling cups, and has for its object to provide a cup which will deliver a 15 uniform stream without the objection of attendant pulsations which cause an uneven discharge of the water from the cup. These pulsations are due as a rule to the presence of air mingling with the stream before its 20 final issue from the cup, the air affecting the density of the stream, and interfering with its otherwise uniform character. Specifically, my invention may be considered as an improvement on the structures of the 25 drinking faucets forming the subjects-matter of U. S. Letters Patent No. 994,747, dated June 13, 1911, and No. 979,489, dated December 27, 1910, issued to J. P. Heeney, reference to which will indicate the particulars in which my improvements differ therefrom. The advantages of the present invention will be apparent from the following detailed description in connection with the 30 accompanying drawing in which—

Figure 1 represents a middle vertical section taken through the faucet, parts being in elevation; Fig. 2 is a top plan of the faucet; Fig. 3 is a horizontal section on the line 3—3 of Fig. 1, looking up; and Fig. 35 4 is an elevation of the faucet.

Referring to the drawings, 1 represents a pipe fitting through which water under sufficient head is supplied to the faucet. The faucet proper comprises a hollow member 45 or cup 2 having a bottom inlet passage-way *a* communicating with the passage-way of the pipe. Screwed into the inlet *a* within the cup 2 is a hollow post 4 on which is formed an annular flange 5 spaced from the inner 50 wall of the cup, a series of ports *o* being formed below the flange for the discharge of the water into the cup, the flow of the water through said ports being regulated by the head 6 of the adjusting screw-valve 55 6' operating through the upper terminal

wall or closed end of the post 4. The top of the cup is closed by a screw cap 7 which projects beyond the outer wall of the cup, the said screw cap being provided with a marginal rim or flange 8 which is beaded 60 over the edge of a hood or bonnet 9, the said hood being formed with a bottom depression which, when the parts are assembled forms with the member 7 a chamber 10 across which the water is projected in its 65 discharge from the cup 2, the projection of the water into the chamber 10 being in the form of individual streams issuing through the comparatively restricted openings formed in the screw-cap 7 and disposed at 70 equal radial distances from the center of the screw-cap, said center being imperforate. Formed along the edge of the hood 9 are a series of substantially semi-circular depressions or arched recesses 11 which span 75 the relief openings 12 disposed along the outer edge of the screw-cap immediately adjacent the rim 8, said relief openings serving to discharge the water downward should mischievous persons attempt to choke off 80 its normal flow through the central comparatively large opening or passage-way *O* formed in the hood 9. When the opening *O* is left undisturbed very little water will escape through the relief ports or openings 85 12; but should any one attempt to squirt a stream by partially closing with his finger the discharge end of the opening *O*, no stream of any consequence will be projected through the reduced opening, but the water 90 will on the contrary seek an outlet through the recesses 11 and relief openings 12, discharging in a direction (downwardly) in which it can do no harm. Should the pressure in the pipe 1 be low, the degree of discharge through the relief ports 12 under 95 normal service conditions may be regulated by a rotation of the hood 9 through a given arc, it being possible by the present arrangement to cut off the flow through the ports 12 altogether by turning the hood sufficiently to bring the recess 11 out of register with the relief ports.

It will be seen from the foregoing that the roof of the chamber 10 presents an imperforate portion of the hood 9 to the jets projected through the openings *o*; and that the final discharge opening *O* of the hood is axially in line with the central imperforate portion of the screw-cap 7, or mem- 105 110

ber spanning the upper end of the cup 2. Thus the opening O of the hood is out of alinement with the openings o of the screw-cap. In drinking faucets of the character 10 here described in which the openings in the screw-cap are in alinement with corresponding openings in the hood, the bubbling of the drinking stream is not uniform but spasmodic, owing to the invasion of the chamber 10 by atmospheric air which causes the fountain to pulsate or heave, thereby failing to present to the drinker a column of water of uniform height. This effect is altogether overcome by my present improvement. The 15 jets issuing from the openings o impinge against the imperforate portion of the roof of the chamber 10, being thereby broken up, and then intermingling as they approach the large opening O and forming a solid 20 water column whose height of projection above the hood 9 is substantially uniform. There are practically no fluctuations to this column and drinking from the fountain is attended with no inconvenience. The members 7 and 9 when assembled form a hollow 25 or chambered cap-piece for the cup 2 as

obvious from the drawing. The details shown may of course be departed from in a measure without affecting the nature or spirit of the invention.

30

Having described my invention what I claim is:

In a drinking faucet of the character described, a hollow cap-piece comprising an inner member and an upper hood therefor 35 forming a water collecting chamber therewith, the edge of the hood engaging the adjacent face of the inner member, and provided with a series of depressions or arched recesses, the outer edge of the inner member being provided with relief ports 40 spanned by the arched recesses aforesaid, whereby communication is established between the chamber of the cap-piece and the atmosphere.

45

In testimony whereof I affix my signature in presence of two witnesses.

ERNEST E. WANGELIN.
